United States Patent Office

Des. 184,992
Patented Apr. 28, 1959

184,992

SOFA

Margaret M. Foulkes, Bloomfield, N.J.

Application August 9, 1957, Serial No. 47,295

Term of patent 14 years

(Cl. D15—11)

Fig. 1

Fig. 2

Fig. 3

Fig. 1 is a front perspective view of a sofa embodying my design, the retractable arms thereof being inoperative position;

Fig. 2 is a similar view showing the arms extended; and Fig. 3 is a rear perspective view thereof.

I claim:

The ornamental design for a sofa, as shown and described.
